SPARK PLUG

Rollin Abell, Chatham, Mass.

Application January 17, 1939, Serial No. 251,285

4 Claims. (Cl. 123—169)

My invention relates to spark plugs such as are employed for internal combustion engines and an object of the invention is to provide a novel and highly efficient spark plug having improved insulating means resulting in higher insulated efficiency which may be made inexpensively and in relatively smaller sizes of plugs.

A further object of the invention is to provide a simplified construction of spark plug in which the spark is discharged in a novel manner adapted for the projection of a better volume of spark at a given voltage or the production of a satisfactory volume of spark at a reduced voltage as compared with other spark plugs upon the market.

With the above and other objects in view I have illustrated in the accompanying drawing preferred embodiments of my invention and wherein:

Fig. 1 shows a central vertical section through a simplified form of my invention.

Fig. 2 represents a central vertical section of one of my spark plugs, the essential features of which are like those of Fig. 1 and in addition includes a protective covering for the insulating member.

Fig. 3 is a slightly modified form of the construction shown in Fig. 2, the principal difference being in the formation of the lower or sparking end of the plug, and

Fig. 4 again shows a slightly modified form of construction wherein the end of the electrode finishes below the insulating tube and flush with the lower end of the metal shell.

By the use of a thin-walled tube of heat resisting glass and the employment of cement as between the said glass and the electrode, a more efficient plug is produced, better adapted to withstand severe conditions of use for much longer periods of time than other spark plugs now on the market.

Referring to the characters of reference marked on the drawing, 10 represents an outer steel shell or supporting member, the main body of which may have an enlarged shouldered surface 11 to form a head for the application of a wrench by means of which the plug may be screwed into the cylinder head of a gasoline motor. The reduced lower portion of this shell member is threaded as at 12 to threadably engage a tapped hole in a cylinder head, not shown. The central portion of this shell is bored to receive an insulating member 13 that may finish flush at its lower end with the threaded lower end portion 12 of the member 10. In Fig. 1 the insulating member 13 extends above the member 10 and is provided with a bore therethrough to receive an electrode 14 which extends through the length of the insulating member and is provided with a washer 15 and a riveted head 16 to support the electrode against any tendency to move upward and outward. In this connection it will also be noted that a shoulder 17 is formed on the member 13 better to hold it in position as against the shouldered shell. A terminal 18 is threadably attached to the upper end portion of the electrode for the attachment of ignition wires, not shown.

I also provide a filling of cement 19 around the electrode as between it and the tubular insulating member 13 to insure a complete closure as between the two parts so as to prevent gas leakage therethrough, from the motor. A filling of cement 20 is also placed between the insulating member and the shell where the former extends through the latter to prevent leakage of gas as in the previous instance. In the form shown in Figs. 2, 3 and 4, where a protective covering 21 of suitable insulating material surrounds the insulating member 13, the shell in addition to the lower reduced threaded portion 11 is provided with an upwardly extended reduced central portion 22 that is also threaded as at 23 for the attachment of the protective covering 21, being applied in spaced relation to the tubular insulating member. The upper inner end of this covering 21 is threaded to receive the threaded terminal 18 which is threadably attached as in Fig. 1 to the threaded portion of said insulator.

This member 21 is of a general cylindrical form having a tapered outer surface and a central hole 24 to surround the tubular insulating member 13. As shown in Figs. 2, 3 and 4, the terminal may be screwed into the covering 21 and seated against the upper end of the electrode while the lower end of the electrode as seen in Figs. 2 and 3 finishes flush with the lower end of the tubular insulating member and the shell. A filling of cement is also used in this form as between the electrode and the tubular insulating member to tightly close them together.

In Fig. 3 I have shown a construction very similar to that shown in Fig. 2 except that the tubing insulator is relatively thicker and has an annular bevel 25 formed on its outer lower end portion that is fitted against an internal annular bevelled shoulder 26 formed in the lower end of the threaded portion of the outer shell 10. In this form the insulating tube would be placed in the casing from its upper end and secured against longitudinal movement by the positioning of the terminal. A filling of cement 19 is also employed in this form as between the electrode and the insulating tubing to prevent gases from passing through the tube.

Fig. 4 is also constructed along the general lines of Figs. 2 and 3 and like those forms includes an insulating covering 21 that is threadably attached to the shell and is tapped to receive a threaded terminal member which is placed in

the upper end above the insulating tube and is seated against the upper end of the electrode. In this form the insulating tube does not extend clear down to the firing end of the shell 12 leaving a space to accommodate a head 16a on the end of the electrode forming an annular gap 27 between the end of the shell and forming a smooth surfaced lower end to the plug to expedite cleaning. This form of plug like those before described is also provided with a filling of cement 19 as between the electrode and the insulating tube. The insulating tube heretofore referred to is made of heat resisting glass, borosilica glass, quartz or may embrace other materials as equivalents which have substantially the same functional characteristics when employed in the manufacture of spark plugs.

From the description thus far it will be observed that in the operation of the present spark plug, the electrodes are arranged with relation to each other to provide the standard or desired gap and to the insulation interposed between them, so that the spark sweeps across the surface of the insulation, thus providing a path of reduced resistance. Also it has been found that the present spark plug possesses the ability to clean from the insulating surface soot, oil or carbon which may deposit thereon, thus enabling the plug to be used under conditions in which prior plugs have quickly become fouled. The reasons for the self-cleaning feature of the present plug are not entirely understood, but it is believed that the corona which is undoubtedly formed and the accompanying "corona wind" assists materially in the removal of deposited soot, oil or carbon from the insulating surface between the electrodes.

The present construction of the spark plug is simple, may be manufactured at minimum expense and in its preferred form contemplates a double insulation with the inner insulator composed of an electrically efficient heat resisting glass such as the borosilica glass now commercially obtainable under the trade name "Pyrex."

By the use of the term "thin" as employed in my claims, I intend to define a thickness of glass sufficiently small that the thickness of the insulating materials now commercially employed between the inner and outer electrodes in the manufacture of spark plugs for the same operating conditions at least is several times as great.

As a result thereof, efficient transfer of heat from the inner electrode to the outer member is accomplished.

The glass need only be sufficiently thick to prevent it being punctured by the electrical potential applied between the inner and outer electrodes. Furthermore, the glass is desirably of less thickness than the length of the spark gap between the electrodes as shown in Figure 3 but may be of a thickness somewhat greater than the length of the spark gap as shown in Figure 1.

By the use of the term "heat resisting glass" as employed in the claims, I intend to embrace quartz as well as borosilica glass such as "Pyrex," although obviously it is my intention to embrace other materials as equivalents which have substantially the same functional characteristics when employed in the manufacture of spark plugs.

Having thus described my invention, what I claim and desire to secure by Letters Patent is:

1. A spark plug comprising an outer metallic member having an elongated bore therethrough, said member radially enlarged outwardly of its

inner end to provide a wrench engageable portion, said member externally screw threaded on its inner end portion and having said bore of less diameter toward the outer end of the member, an inner electrode extending through said bore, a thin walled tube of vitreous refractory insulating material in said bore about said electrode and of an external configuration corresponding with the internal configuration of said bore whereby not to be forced out of the bore by a pressure at the inner end of the plug, a cement seal between the electrode and the outer end portion of said tube, said tube terminating adjacent one end of the bore to provide a spark gap between said electrode and said member, and said tube having a wall thickness not substantially greater than the length of said spark gap.

2. A spark plug comprising an outer metallic member having an elongated bore therethrough, said member radially enlarged outwardly of its inner end to provide a wrench engageable portion, said member externally screw threaded on its inner end portion and having said bore tapering whereby it is of less diameter toward the outer end of the member, an inner electrode extending through said bore, a thin walled tube of vitreous refractory insulating material in said bore about said electrode and of an external configuration corresponding with the internal configuration of said bore whereby not to be forced out of said bore by a pressure at the inner end of the plug, a cement seal between the electrode and the outer end portion of said tube, said tube of fused quartz whereby during use of the spark plug the tube at its outer end portion will remain cool enough for the effective use of cement as a seal between the electrode and the outer end portion of the tube, said tube terminating adjacent one end of the bore to provide a spark gap between said electrode and said member, and said tube having a wall thickness not substantially greater than the length of said spark gap.

3. A spark plug comprising an outer metal member having an elongated bore therethrough, said member radially enlarged intermediate its ends and externally threaded at the inner and outer sides of said enlarged portion, an inner electrode extending through said bore, a thin walled tube of vitreous refractory insulating material in said bore about said electrode and extending beyond the outer end of said member and terminating adjacent the inner end thereof to provide a spark gap between the electrode and member, a cement seal between the electrode and the outer end portion of said tube, said tube of fused quartz whereby during use of the spark plug the tube at its outer end portion will remain cool enough for the effective use of cement as a seal between the electrode and the outer end portion of the tube, said tube having a wall thickness not substantially greater than the length of said spark gap, and a protective molded body of insulating material threaded to the outer threaded portion of said metal member and disposed about the outer portion of said tube.

4. The combination as in claim 3 including a terminal threaded into the outer end of said molded body and electrically connected with said inner electrode.
